DRAWER SLIDE

Filed May 15, 1928

UNITED STATES PATENT OFFICE

DIRK B. K. VAN RAALTE, OF HOLLAND, MICHIGAN, ASSIGNOR TO CHARLES P. LIMBERT COMPANY, OF HOLLAND, MICHIGAN, A CORPORATION OF MICHIGAN

DRAWER SLIDE

Application filed May 15, 1928. Serial No. 277,831.

This invention relates to a drawer slide. It is an object and purpose of the present invention to provide a very practical type of extension drawer slide in which the full width 5 of an enclosing casing can be utilized for drawer space and in which the number of sliding parts required for a fully extensible slide are reduced through the utilization of the depending sides of the drawer below the 10 bottom thereof in place of an additional sliding element. A further object of the invention is to make a drawer slide of this character which is cheap to produce and with which the drawer can be readily disengaged from 15 the slide when in its extended position.

The invention comprises many novel details of construction and organizations and arrangements of parts for effectively attaining the ends stated, together with many others not at this time pointed out but which 20 will appear upon understanding of the invention had from the following description, taken in connection with the accompanying drawing, in which,

25 Fig. 1 is a fragmentary perspective view illustrating a drawer equipped with the slide of my invention.

Fig. 2 is a fragmentary vertical section through a drawer holding case or cabinet and 30 showing the drawer and drawer slide therein.

Fig. 3 is a fragmentary plan view of the construction shown in Fig. 1, and

Fig. 4 is a fragmentary perspective view of the forward end of one of the slide members 35 to which the drawer is connected.

Like reference characters refer to like parts in the different figures of the drawing.

The casing or cabinet in which the drawer is mounted may be of any desired character 40 such as a desk pedestal, a filing cabinet, or the like, having vertical sides 1, a top 2, a back 3 and one or more horizontal partitions 4 dividing the cabinet into drawer receiving recesses.

45 On the upper side of each partition 4 a pair of spaced apart parallel slide members 5 are permanently secured each having a longitudinal groove 6 in its outer edge. Associated with each of the slide members 5 is a second slide member 7 located at the outer edge of

said member 5, which at the outer edge is longitudinally grooved for its entire length, as indicated at 8. A flat metal plate 9 is permanently secured to the upper side of each of the slide members 7 near the rear end thereof, extends inwardly across the adjacent slide member 5 and has a downturned lip 10 coming against the inner side of said member 5, as shown in Figs. 1 and 2.

55 Each of the members 5 near its front end is equipped with a stop pin 11 which extends, at its outer portion, into the groove 6. Each of the adjacent slide members 7 carries two pins 12 and 13, the former ahead of and spaced from the latter, and both extending into the 60 adjacent groove 6, whereby when the slide members 7 are drawn forward a predetermined distance the pins 12 engage against the pins 11 and stop further outward movement 65 of the members. 70

The drawer of wood, preferably, has spaced 75 vertical sides 14, the usual front and a back 15 with a bottom 16 which is located above the lower edges of the sides, front and bottom a distance somewhat greater than the thickness of the slide bars 5 and 7. The back 15 at its lower edge is notched at two spaced apart points to provide the notches 17, the length of each notch being slightly greater than the combined widths of the two slide 80 members 6 and 7, which pass therethrough.

Each of the members 7 adjacent its front end is equipped with a pin 18 similar to the pin 11 and extending at its outer end into the groove 8 of said member 7. The depending portions 85

14^a of the sides 14 below the bottom 16 carry two spaced apart pins 19 and 20, the former being located ahead of and spaced from the latter, which extend into the grooves 8 of the adjacent members 7, it being evident that 90 the drawer may move outwardly on the slide bars 7 until pins 19 come against the pins 18.

When the drawer is pulled to its outermost position, as shown in Figs. 1 and 3, the pins 19 are located a short distance ahead of 95 notches 21 made in the bars 7 at their outer edges and from their upper sides downwardly to the grooves 8. By moving the drawer back a short distance, or until the pins 19 come directly under the notches or openings 21, 100

the front end of the drawer may be lifted to disengage the pins 19 from the slide bars 7. The drawer may then be pulled farther forward or until the pins 20 come directly beneath the notches 21 whereupon the drawer 5 may be completely disengaged from the slide members 7 by lifting pins 20 through said notches.

It is evident that when the drawer is retracted into the cabinet the slide members or bars 5 and 7 lie alongside of each other and the depending portions 14^a of the drawer sides lie alongside of the outer slide members 7. When the drawer is pulled outwardly the drawer moves outward on the slide bars 7 and said slide bars 7 move outwardly over the partitions 4 and with respect to the fixed slide members 5. The outward movement of the drawer is limited when the pins 18 and 19 and 20 11 and 12 come into stopping engagement with each other. In such position the drawer is fully extended from the cabinet.

The drawer slide described is of simple but very practical construction. It is economical 25 in the utilization of the depending portions of the sides below the bottom 16 as a part of the extension slide construction for the drawer. This permits the use of only two bars at each side of the drawer yet at the same time 30 permits a complete withdrawal of the drawer from the case or cabinet within which it is normally located. Various changes in minor constructive details may be resorted to without departing from the invention defined in 35 the appended claim, and the invention is to be considered comprehensive of all forms of structure coming within the scope of said claim.

I claim:

40 In a drawer guide construction, a horizontal support, a pair of bars each grooved longitudinally at its outer edge permanently secured to the support in spaced apart relation, a second pair of bars each grooved longitudinally at its outer edge located one alongside the outer edge of each of the first bars, guide pins extending from the second bars into the grooves of the first bars, a stop adjacent the front end of the groove in each 45 of the first bars, a drawer having vertical sides and a bottom located a distance above the lower edges of said sides located over said bars, guide pins extending inwardly from the sides of the drawer at points below the bottom 50 thereof into the grooves of the second mentioned bars and a stop adjacent the front end of the groove in each of the second mentioned bars, each of said bars a short distance back of its outer end having a notch cut therein at its grooved edge from its upper side 55 downwardly to the groove therein for the purposes described.

In testimony whereof I affix my signature.
